UNITED STATES PATENT OFFICE.

CARL D. BROWN, OF HOPEDALE, MASSACHUSETTS, ASSIGNOR TO DRAPER CORPORATION, OF HOPEDALE, MASSACHUSETTS, A CORPORATION OF MAINE.

FEELER MECHANISM FOR LOOMS.

Application filed May 22, 1922. Serial No. 562,581.

To all whom it may concern:

Be it known that I, CARL D. BROWN, a citizen of the United States, and a resident of Hopedale, in the county of Worcester and 5 State of Massachusetts, have invented an Improvement in Feeler Mechanisms for Looms, of which the following description, in connection with the accompanying drawings, is a specification, like characters on the 10 drawings representing like parts.

This invention relates to feeler mechanisms for looms.

The repeated contact of the engaging end of the feeler with the filling on detecting 15 beats is liable to cause injury to the filling especially where the filling is of a high count or fine character. One of the causes contributing to this objectionable effect upon the filling is that the lay and consequently 20 the shuttle box, shuttle and filling carrier move in the arc of a circle about the lay rock shaft as a center as the lay beats up, whereas, the feeler as now generally constructed is mounted for movement towards and from 25 the front of the loom in a different path. Usually the feeler is mounted to move towards and from the front of the loom in a straight path or at least in a horizontal plane so that inasmuch as the frontward 30 movement of the feeler is effected by frontward pressure of the surface within the shuttle which is moving in a curvilinear path, there is a constant rubbing friction or cutting action of the filling taking place on 35 each detecting beat.

One of the important features of the present invention is to provide a feeler mechanism wherein the feeler shall have a compensating tip constructed and arranged so 40 that notwithstanding the feeler moves in a substantially straight path and the filling carrier and the shuttle move in a curvilinear path, the filling will be preserved from cutting action or injury by the feeler tip.

In the present invention the feeler mechanism is of the "side swipe" type and the feeler tip is constructed and arranged to hold the feeler from partaking of its side swipe movement by engagement with a working 45 supply of filling, and by such engagement also to compensate for the difference in the path movement of the feeler and filling carrier.

The novel features and new combination 50 of parts will best be made clear from the

following description and accompanying drawings which show one good practical form of the invention.

In the drawings:

Fig. 1 is a plan view partly in section 60 showing the feeler mechanism of the present invention and its action when on a detecting beat a working supply of filling is present in the shuttle;

Fig. 2 is a view similar to that of Fig. 1 65 but showing the action of parts when the filling is substantially exhausted on a detecting beat;

Fig. 3 is an enlarged section fore and aft of the loom, showing more particularly the 70 different paths of movement of the filling carrier and the feeler as the lay beats up;

Fig. 4 is an enlarged detail showing more particularly the construction and mounting 75 of the feeler tip; and

Fig. 5 is a detached detail of the feeler and feeler slide.

The filling replenishing mechanism and the train of mechanism between it and the feeler for effecting replenishment of filling 80 are not herein shown because they are and may be of any usual and well-known construction and the details thereof form no part of this invention.

The feeler stand, as indicated in Figs. 1 85 and 2, is of appropriate character for supporting the feeler and its connected parts and consists of a base portion 1 surmounted by a cap 2 secured to it by screws 3. The feeler stand may be provided with a flange 90 portion 4, Fig. 1, having a slot 5 by which the feeler stand may be secured to the loom frame through the screws 6.

The base portion 1 of the feeler stand is hollowed out as indicated at 7 to form a 95 chamber for the deflection of the spring 8, the front end portion of which is connected to a stationary or swivel block 9 and the rear end portion of which is connected at 10 to the frontwardly extending portion of 100 the feeler 11. The ends of the spring 8 may be connected to the swivel block 9 and to the frontward extension 10 of the feeler by seating the ends of the spring in these respective parts, and the spring may be clamped 105 in the block 9 by a screw 12. These features may be varied with respect to details, the essentials being that the two ends of the spring 8 be secured, one to the swivel block 9 and the other to the feeler. Between 110

- the feeler and swivel block 9 the base portion 1 has an inwardly extending lug 13 against which the spring 8 normally bears when it is in its extended or straightened position.
- 5 The feeler stand has a rear bearing provided with a guideway for a slide 14 and the slide 14 has a slotted portion 15 through which the feeler 11 extends. The slide 15 is connected to a transmitter 16 which forms 10 part of a train of mechanism for effecting replenishment of filling when the feeler calls the change. The slide 14 may be conveniently held in its guideway by the cap piece 2.
- 15 The lay 17 is provided with the usual shuttle box having an opening 18 in its front wall. The shuttle 19 is provided with the usual bobbin holding jaws 20 for supporting the 20 bobbin 21 on which the filling 22 is wound, and the front wall of the shuttle has an opening 23, the construction being such that the feeler 11 may enter the shuttle through the openings to feel for filling.
- 25 The lay 17 is carried by the usual lay swords 24 which extend downwardly to the lay rock shaft as usual and it is given its beat up movement by the usual pitman connection to the driving or crank shaft, thus 30 the lay and perforce the shuttle box, the shuttle and the filling carrier within the shuttle move towards and from the front of the loom in the arc of a circle, the center of which is the lay rock shaft. This condition 35 is indicated in Fig. 3 wherein the dotted position *a* represents the filling carrier when the lay is in its rearward or back position. *b* represents the filling carrier when the lay is moved forwardly to cause the filling in 40 the shuttle to be engaged by the feeler, and the full lines, Fig. 3, represent the frontmost position of the lay and the filling carrier.
- Still referring to Fig. 3 it will be noted that 45 the feeler 11 is mounted for movement towards and from the front of the loom in a horizontal plane, whereas, as above indicated, the lay and its connected parts move towards and from the front of the loom in a vertical arc. Thus, in the absence of 50 means to prevent, the filling in the shuttle will be subjected to a rubbing and cutting action due to the difference in the paths of movement of the filling and the engaging portion of the feeler as the lay moves forwardly. This rubbing or cutting action 55 upon the filling is graphically represented in Fig. 3 where it will be noted that the filling carrier, represented by the dotted lines *b* gradually rises as it moves forwardly in contact with the feeler, whereas the feeler itself moves in a straight path forwardly, consequently there is a relative movement between the filling and the engaging end of the feeler in a vertical 60 direction tending to cut or injure the filling.

The feeler in the present invention is provided with a compensating feeler tip which compensates for the difference in the path of movement of the filling carrier and feeler on each detecting beat. In the present instance, the feeler 11 has its end portion bifurcated as at 25, and between the bifurcated portions 25 is rotatively supported the feeler tip 26. The tip 26 is rotatively supported upon the pin 27 secured in the bifurcated ends 25 of the feeler and passing through the feeler tip. The feeler tip has circumferentially extending toothed portions 28 which alternate with the depressed portions 29 so that the feeler tip when engaged with the filling may be turned by the filling relative to the feeler as the lay beats up.

The compensating feeler tip is preferably formed with the central portion, midway between the ends, of greater diameter than the end portions, as indicated more clearly in Fig. 4.

When a working supply of filling is present in the shuttle on a detecting beat, Fig. 90 1, the compensating tip 26 of the feeler engages and sinks into the filling and as the lay beats up its changing path of movement causes the compensating tip to move or rotate in a vertical plane relative to the feeler and with the avoidance of the rubbing or cutting action against the filling. Since the feeler is not free to be moved longitudinally along the shuttle under the conditions noted, the spring 8 will be buckled 100 or deflected, as indicated in Fig. 1, as the feeler is pushed forwardly, but such action of the spring will have no effect in moving the feeler longitudinally of the shuttle.

When however the filling is substantially 105 exhausted on a detecting beat the buckling action of the spring 8 as the feeler is moved forwardly will cause the feeler to be moved in a direction longitudinally in a direction of the shuttle, as indicated 110 in Fig. 2, because at such time there is not sufficient filling in the shuttle to restrain the feeler from such movement, and filling replenishment will be called through 115 the train of mechanism described.

What is claimed is:

1. In a feeler mechanism for looms, the combination of the lay and shuttle-box mounted for movement toward and from the front of the loom in a vertically curved path, a feeler mounted for movement toward and from the front of the loom in a horizontal path, and a compensating feeler tip mounted on the feeler for movement relative thereto in a vertical plane by the filling as the lay moves forward in its curved path on a detecting beat to prevent injury to the filling and compensate for the difference in the direction of movement of the feeler and filling.

2. In a feeler mechanism for looms, the combination of the lay and shuttle-box mounted for movement toward and from the front of the loom in a vertically curved path, a feeler mounted for movement toward and from the front of the loom in a horizontal path, and a feeler tip mounted on the feeler for rotative movement about the filling carrier by the frontward pressure of the filling as the lay beats up on a detecting beat to compensate for the difference in direction of movement of the feeler and lay. 40
5. In a feeler mechanism for looms, the combination of the lay and feeler mounted for movement toward the front of the loom in different paths on a detecting beat, and a compensating feeler tip mounted on the feeler and moved relatively thereto by the frontward pressure of the filling due to the different paths of movement of the lay and feeler as they move frontwardly on detecting beats. 45
10. In a feeler mechanism for looms, the combination of the lay and feeler mounted for movement toward and from the front of the loom in different paths, and a feeler tip mounted for movement relative to the feeler and in the vertical plane of the lay movement by the frontward pressure of the filling on a detecting beat to avoid injury to the filling due to the different paths of movement of the feeler and lay. 50
15. In a feeler mechanism for looms, a feeler mounted at the front of the loom and having a filling engaging tip mounted for rotative movement on the feeler in a plane at right angles to the axis of the wound mass of filling engaged by it. 55
20. In a feeler mechanism for looms, the combination of a feeler mounted for movement toward and from the front of the loom, a roller mounted on the feeler for rotative movement relative thereto at right angles to the axis of the filling carrier in the shuttle on a detecting beat. 60
25. In a feeler mechanism for looms, a feeler having a filling engaging tip mounted for rotative movement in a plane at right angles to the longitudinal axis of the bobbin in the shuttle, and provided with circumferentially extending projecting portions constituting filling engaging teeth. 65
30. In a feeler mechanism for looms, the combination of a feeler mounted for movement toward the front of the loom by
35. In a feeler mechanism for looms, the combination of a feeler mounted for movement toward the front of the loom in a horizontally curved path, a feeler tip mounted on the feeler for rotative movement about the filling carrier by the frontward pressure of the filling on a detecting beat, and a feeler tip mounted on the feeler for rotative movement about the filling as the lay beats up. 70

In testimony whereof, I have signed my name to this specification.

CARL D. BROWN.
